AND WILLIAM JOHN McDONALD, OF PRESTON, AUSTRALIA

HYDRAULICALLY OPERATED AIR COMPRESSOR AND THE LIKE

Application filed August 5, 1929, Serial No. 383,598, and in Australia August 13, 1928.

This invention relates to improvements in and connected with hydraulically operated air compressors and refers especially to compressors for charging receivers and for inflating pneumatic tires of motor vehicles and other inflatable sacks or bags.

The object of the present invention is to provide a hydraulically operated device of simple, efficient and compact construction adapted to supply air or the like under pressure for charging receivers or inflating pneumatic tubes or sacks.

We accomplish the abovementioned objects by providing, in hydraulically operated air compressor mechanism, a valve or valves for supplying water under pressure to and for discharging it from the compressor, and resilient means associated with a member controlled by the water supplied to the compressor for rapidly opening and closing the valve or valves at regular intervals.

The compressor may be of the type wherein air is compressed in a chamber by the direct displacement of water, the said chamber being fitted with parts provided with suction and discharge valves of approved type for permitting the ingress and egress of air.

More specifically the invention comprises a compressor chamber having inlet and discharge pipes projecting thereinto and having closed ends, a sleeve valve oscillatively mounted on the ends of the inlet and discharge pipes, ports in the inlet and discharge pipes adapted to register with coacting ports in the sleeve valve, a float or floats in the chamber, and mechanism controlled by the float or floats for periodically actuating the sleeve to open and close the inlet and discharge ports.

The valve controlling mechanism is preferably of the snap action type in order that rapid opening and closing movements may be effected.

In order that the invention may be readily understood reference will now be had to the accompanying sheets of explanatory drawings wherein:

Figure 1 is a view in sectional elevation of a hydraulically operated air compressor con-

structed in accordance with the present invention.

Figure 2 is a view in sectional plan of Figure 1.

Figure 3 is a view in sectional side elevation of part of the invention which will be hereinafter fully described, and

Figures 4 and 5 are views in sectional elevation of Figure 3 taken on the dotted lines 4 and 5 respectively.

Figure 6 is a view in sectional elevation of a modified form of the invention.

Figure 7 is a view in sectional side elevation of Figure 6.

Figure 8 is a sectional plan of Figure 6 taken on the dotted line 8—8.

Figure 9 is a view in perspective of a detail which will hereinafter be fully described.

In these drawings the reference numeral 10 designates an air-tight chamber of cylindrical formation having its upper and lower ends fitted with cover plates 11. The cover plate at the upper end of the cylindrical chamber is provided with an air inlet port 12 having a spring or gravity actuated suction valve 13 of approved type, and a port 14 furnished with a delivery pipe 15 adapted to discharge compressed air either to a receiver (not shown), an automobile tire, or other device.

Parallelly disposed inlet and discharge pipes 16 and 17 are fitted to the lower cover plate and project into the cylindrical chamber, and the upper ends thereof are connected by a horizontal pipe 18 provided with a centrally disposed partition 19 isolating the inlet and discharge portions thereof.

A plurality of ports comprising longitudinally disposed slots 20 are formed in the horizontal pipe on the inlet side of the partition and a series of slots 21 are arranged in the horizontal pipe on the discharge side of the partition.

These ports or slots 21 preferably are greater in number than the ports or slots 20 and the discharge pipe 17 may be larger than the inlet pipe.

A sleeve 22 is fitted externally on the horizontal pipe 18 connecting the ends of the inlet and discharge pipes and suitable stops (not shown) may be provided to permit of

a limited oscillatory movement thereof. This sleeve 22 is arranged to cover the inlet and discharge ports 20 and 21 in the horizontal pipe and is provided with a plurality of ports 23 and 24 conforming in shape to and adapted to register therewith. It will be understood that, when the slots in the inlet portion of the horizontal pipe register with the coating ports in the sleeve, the discharge ports on the opposite side of the partition are closed as they are out of register with the corresponding ports formed in the sleeve.

A bracket or pedestal 25 is arranged within the chamber adjacent to the inlet and discharge pipes and may be fitted to or formed integrally with the lower cover plate.

The bracket or pedestal 25 is provided with a laterally projecting pivot pin 26 and an arm 27 pivotally mounted thereon is loosely engaged by jaws 28 or like members fitted to the exterior of the oscillatable sleeve.

An arm 29 of curved formation shaped to pass partially around the horizontal pipe within the chamber is fitted to or formed integrally with the first-mentioned or operating arm 27 and the free end thereof is pivotally connected to one end of a plunger 30 slidably mounted in a co-axial tubular member 31 pivotally supported on a bracket 32. The bracket 32 is situated on the opposite side of the horizontal pipe 18 to the bracket 25. A compression spring 33 encircles the telescopically connected members 30 and 31 and its opposite ends bear against collars on each member near the pivot point thereof.

This last-mentioned arrangement constitutes a toggle and the pivotal supports for the same are constructed in such a way as to obviate any undue lateral movement when the toggle is displaced angularly in either direction.

A further arm 34, rigidly associated with the operating arm of the sleeve valve, is pivotally connected at or near its free end to the lower end of a vertical rod or spindle 35, the upper end of which has a lost motion connection with a sheet metal or other approved form of float 36 arranged within the chamber.

In one form of the invention the lost motion connection may be effected by providing two collars 37 on the control rod adapted to engage an intermediately disposed abutment 38 fitted within an opening formed centrally in the float.

In operation, the inlet pipe 16 is connected by approved means to a source of water under pressure. It will be understood that, when the float 36 is in its lowermost position, the inlet ports 20 are open and the discharge ports 21 closed by means of the associated sleeve valve 22. Water thus passes into one end of the horizontal pipe and thence into the cylindrical chamber through the ports 16 and 23 in the inlet valve.

As the water rises in the chamber, the air valve 13 previously mentioned is maintained on its seat by means of the spring associated therewith and the air in the chamber is consequently compressed. When the air pressure reaches a desired magnitude, a valve 39 in the delivery pipe 15, receiver, or in a tire connected thereto, is automatically opened and the compressed air is discharged from the chamber.

The float is elevated as the water level rises within the chamber and, after a predetermined upward movement, is effected, the abutment 38 on the float engages with the upper collar 37 on and elevates the control rod 35. This upward movement of the control rod causes a corresponding displacement of the second-mentioned arm 29 on the plunger 30 and pivotally mounted tube associated therewith, and, during this initial movement, the spring 33 is compressed by the plunger and, immediately the dead centre position is passed, the spring is relieved and forces the plunger outwardly until further angular movement of the tubular member is arrested by the arm 29 contacting with the sleeve 22.

During this movement, the control rod 35 is projected upwardly, and the upper collar 37 thereon is moved away from the abutment on the float. Simultaneously with these movements, the operating arm 27 is displaced to actuate the sleeve valve 22 through the medium of the jaws 28 fitted thereto as previously described.

It will be understood that no movement of the sleeve valve takes place till after the dead centre position of the toggle members 30 and 31 has been reached, after which the valve rapidly moves across to the discharge position.

The level of water within the chamber immediately commences to fall as the water is discharged through the discharge ports 21 and 24 of the valve and the pipe associated therewith. The air pressure within the chamber is consequently relieved and immediately it falls below that of the atmosphere, the air valve 13 is opened by the preponderance of pressure on the top thereof.

When the water has fallen to a predetermined level within the chamber, the float engages the lower collar 37 on, and depresses the control rod 35, thus causing the toggle members 30 and 31 to pass their dead centre position in the opposite direction, with the result that the sleeve valve 22 is again rapidly displaced to close the discharge ports 21 and 24 and open the inlet ports 20 and 23, so that the cycle of operations is repeated until the source of water is turned off by means of a cock provided for the purpose.

To prevent any water passing into the air delivery pipe in the event of a defect occurring in the valve mechanism, a float operated cut-off valve (not shown) may be provided

for closing the end of the delivery pipe when the water level exceeds a predetermined maximum.

In the form of the invention illustrated in Figures 6 to 9 of the drawings the cylinder 10 is provided with cover plates 11 and the upper cover plate is provided with an air inlet port having a valve 13 and with an outlet port 14 having a valve 39 therein arranged as hereinbefore described.

10 The lower cover plate is provided with inlet and discharge ports 40 and 41 and bosses depending from the said cover plate and arranged concentrically with the ports are 15 screw threaded to permit water inlet and discharge pipes (not shown) to be detachably connected thereto.

Secured to the top of the lower cover plate in line with the inlet and discharge ports are 20 vertically arranged cylindrical-valve chambers 42 and 43, respectively.

25 These valve chambers 42 and 43 are arranged in communication with the interior of the compressor chamber or cylinder 10 by means of ports 20 and 21 and by corresponding ports 23 and 24 formed in sleeve valves rotatively mounted on the same.

The ports in the valve chambers 42 and 43 and the ports in the sleeve valves 22 surrounding the same are constructed and arranged identically with those shown in Figures 1 to 4 of the drawings.

30 The sleeve valves 22 are retained neatly in position on the valve chambers 42 and 43 by 35 any approved means and axially disposed pedestals 44 project upwardly from the said valve chambers. The upper ends of the pedestals are adapted to support inwardly projecting pivot pins 45 and these pivot pins 40 are connected by toggle members to a horizontally disposed pivot member 46 supported in a bracket 47 fitted to the lower cover plate intermediate the valve chambers 42 and 43.

The toggle members normally are adapted 45 to project at an angle on opposite sides of a vertical plane passing centrally through the chamber 10 and the lower member of each toggle constitutes a straight link whilst the upper member comprises a plunger 30 and 50 tubular member 31 encircled by a compression spring 33 as hereinbefore described with reference to Figures 1 and 2 of the drawings.

The lower member 48 of each toggle is 55 provided with angularly disposed arms 49 having pins 50 or studs projecting laterally therefrom. These pins or studs 50 are adapted upon the angular displacement of the toggle members to contact with an arm projecting radially from the adjacent sleeve 60 valve 22 whereby the valve will be opened and closed by the force of the springs associated with the toggle members when the said members pass over their dead centre positions as hereinbefore described.

65 A bracket 52 depending from the float 36 is

connected by a series of diagonal levers pivoted together at the middle and ends in the form of lazy tongs 53 to the pivot pin 46 supporting the toggle members.

The lowermost levers of the lazy tongs 70 are pivoted to the pin 46 intermediate the lower members of the toggle levers and abutment members 54 and 55 on the said lowermost levers are adapted to contact with and actuate the toggle members upon the opening and closing of the lazy tongs due to the rise and fall of the float within the cylindrical chamber 10.

75 The abutments 54 and 55 are formed on the outer faces of the lowermost pair of levers and the abutments 55 are formed on portions of the levers which extend below the pivot pin 46. The abutment 54 is arranged to bear against one side of the lower toggle members when the float is rising in the chamber 10 80 and the abutment 55 is adapted to bear against the opposite side of the lower toggle members when the lazy tongs are being closed by the descent of the float.

85 The abutments 54 and 55 likewise may 90 serve to limit the movement of the toggles and the oscillating movement imparted to the sleeve valves 22 when they are displaced by the springs upon their central portions being moved beyond the dead centre position in either direction.

95 In order to positively limit the oscillating movement of the valve 22 arms 56 projecting radially from the sides thereof are adapted 100 to contact with pins or abutment members 57 projecting upwardly from the lower end plate.

105 In order to ensure the positive operation of the toggle members and the actuation of the sleeve valves prior to the float reaching the top of the cylinder 10 a lost motion connection is provided between the lowermost levers of the lazy tongs and the float. This lost motion connection may comprise extensions 58 on the ends of the lowermost levers 110 having rods 59 pivotally connected thereto and passing upwardly through passages 60 in the float.

115 The upper ends of the rods 59 are provided with fixed or adjustable abutment members 61 which are so disposed that in the event of the float rising to a predetermined point due to wear of the pivot points of the lazy tongs the toggle members will 120 be positively actuated.

125 Whilst preferred forms of the invention have been described herein, it will be obvious that various modifications and alterations may be made in the construction and arrangement of the device without departing from the spirit and scope of the invention and, consequently, we do not wish to be understood as limiting ourselves by the specific terms employed herein.

We claim:—

1. A hydraulically operated air compressor comprising a chamber having inlet and discharge pipes projecting thereinto and having closed ends, a sleeve valve oscillatively mounted on the ends of the inlet and discharge pipes, ports in the inlet and discharge pipes adapted to register with co-acting ports in the sleeve valve, a float in the chamber, and mechanism controlled by the float for periodically actuating the sleeve valve to open and close the inlet and discharge ports.

2. A hydraulically operated air compressor comprising a compressor chamber having water inlet and discharge pipes communicating with valve chambers disposed within the compressor chamber, a sleeve valve oscillatively mounted on the valve chambers, ports in the valve chambers adapted to register with co-acting ports in the sleeve valve, float controlled mechanism for periodically actuating the sleeve valve to place the inlet and discharge pipes alternately in communication with the compressor chamber, and valve controlled air inlet and outlet ports in the upper end of the compressor chamber.

3. A hydraulically operated air compressor comprising a cylindrical compressor chamber having pipes for supplying water under pressure to and for discharging it from the lower end thereof, a cylindrical pipe located within the compressor chamber and connected to the inlet and discharge pipes, a central partition in the cylindrical pipe, ports in the cylindrical pipe on each side of the partition, a sleeve valve surrounding the cylindrical pipe and having ports therein adapted to be placed in register with the ports in the cylindrical pipe, float controlled mechanism for periodically actuating the sleeve valve whereby the inlet and discharge pipes can be alternately placed in communication with the interior of the compressor chamber, and valve controlled air inlet and outlet ports in the upper end of the compressor chamber.

4. A hydraulically operated air compressor comprising a compressor chamber having cylindrical valve chambers therein communicating with pipes for supplying water under pressure to and for discharging it from the compressor chamber, a sleeve valve oscillatively mounted on the valve chambers and having ports therein adapted to register with ports in the said valve chambers, float controlled mechanism for periodically actuating the sleeve valve to place the inlet and discharge pipes alternately in communication with the compressor chamber, and valve controlled air inlet and discharge ports in the upper end of the compressor chamber.

5. In a hydraulically operated air compressor according to claim 4, a pair of jaws projecting radially from the sleeve valve, an oscillatively mounted arm loosely engaged by

the jaws, a curved arm having a fixed relationship with the first mentioned arm, a coaxially arranged interfitting plunger and tubular member connecting the free end of the second mentioned arm to a pivot located on the opposite side of the sleeve valve to that upon which the arms are mounted, a spring exerting opposing pressures between the plunger and tubular member, a rod connected to an arm fixedly associated with the first mentioned arm, abutments on the rod, and a float slidably mounted on the said rod between the abutments.

6. In a hydraulically operated air compressor according to claim 4, jaws projecting radially from the sleeve valve, an arm loosely engaged by the jaws, a toggle arm or lever having a fixed relationship with the arm engaged by the jaw, a telescopically constructed toggle lever connecting the first toggle lever to a pivot member supported within the compressor chamber, a spring adapted to exert a longitudinal pressure between the two portions of the telescopic lever, a third arm or lever having a fixed relationship with the first mentioned arms, and a lost motion connection between the third arm and the float.

7. A hydraulically operated air compressor according to claim 2, wherein the valve ports communicating with the discharge pipe are of greater dimensions than the ports in the valve communicating with the inlet pipe.

In witness whereof we hereunto affix our signatures.

AUBREY CARLYLE JAMIESON.

JOHN FRANCIS GARDINER.
